(57) **CLAIM**

The ornamental design for an integrated bedsheets set, as shown and described.

DESCRIPTION

FIG. 1 is a front elevational view of an integrated bedsheets set showing my new design;

FIG. 2 is a rear elevational view thereof;

FIG. 3 is a side view, taken from the left side of FIG. 1, the right view being a mirror image thereof;

FIG. 4 is a top plan view thereof;

FIG. 5 is a bottom plan view thereof; and,

FIG. 6 is a perspective view thereof—showing the top sheet of the integrated bedsheets set pulled back for illustrative purposes.

The broken line seen in FIGS. 1 and 6 of the drawing views represents stitching.
